Application December 3, 1937, Serial No. 177,883

38 Claims. (Cl. 226—14)

This invention relates to machines for packing bottles in cases for shipping or storage, the cases comprising cartons, or boxes, made of corrugated board, fibreboard, wood, or other suitable material. More particularly, our invention relates to a packing machine in which the bottles—and this term will be used throughout the specification to include not only the glass containers usually meant by the term "bottle," but also cans and other cylindrical containers, or articles, made of various materials—are advanced in upright position to form a charge which is transferred to appropriate packing mechanism, usually comprising directing mechanism which merely guides the bottles into the case under the influence of gravity. The machine automatically assembles successive charges, each of which is automatically transferred to the packing mechanism, and, in the embodiment of the invention chosen for illustration, dropped through the packing mechanism into its case. The cases, or cartons, are placed in the machine by hand, and, after receiving a charge, are automatically ejected from the machine under the control of the machine operator. The primary object of our present invention is to provide an improved bottle packing apparatus of the type referred to which will automatically pack bottles in cases at a high rate of speed, and which is capable of operating continuously over long periods of time without substantial interruption of the line, or lines, of bottles fed to the packing machine.

The present invention has to do especially with packing machines for packing bottles in cell cases, that is, in cases which are provided with partitions forming individual cells or compartments for the bottles, although the apparatus of the invention can also be used to pack bottles in cases which are not provided with such partitioning devices. The bottles in the assembled charge are arranged in one or more parallel rows, the bottles of each row being in contact with one another. However, the partitions, usually of corrugated board, fibre board or wood, sometimes are as much as $\frac{3}{8}$ in. thick. Hence if the bottles were delivered to the cases in contact with one another, the ends of the bottles would strike the edges of the partitions. Another object of our invention is, therefore, to automatically space the bottles of each row forming the charge so that they will properly enter their respective individual compartments.

Furthermore, both the cartons and the partitioning devices are ordinarily received by the user of the packing machine "in the flat." The

operator of the machine unfolds both by hand and inserts a cell structure in each carton before placing the carton on the receiving table of the packing machine. These partitioning devices are usually made of parallel strips of corrugated board some two or more inches wide and slit from opposite edges and fitted together so as to form the required number of square cells when placed in a carton. These strips are flexible and in unfolding them from the flat the walls of some of the cells, particularly those adjacent the walls of the carton, will usually be bent to one side or the other from their correct position so that they would be in the path of the descending bottles unless straightened before the bottles enter the compartments. Another object of the invention is to provide a particularly effective mechanism for automatically straightening the walls of the individual compartments to receive the bottles.

Although glass bottles, such as are used as containers for beverages, food products, chemicals, etc., are usually made by means of a molding process, they nevertheless vary considerably in diameter. A common arrangement of such bottles when packed in a case provides for four rows of six bottles each, and there is enough variation in diameter of these bottles to cause a possible variation of about an inch in the length of a row of six bottles. This introduces a considerable problem in assembling the charge and properly placing the individual bottles in their respective compartments without causing jamming of the bottles in such a way that the machine has to be shut down and cleared by hand. Accordingly, another object of the invention is to provide a machine which is capable of handling the usual run of bottles of varying diameter without shut-down caused by the jamming of the bottles.

Bottle packing machines are customarily installed in a packing plant to receive the bottles from a previous operation, such as labelling. A further feature of our invention is the provision of a packing machine which is adapted to receive bottles from one, or from two, or from any multiple of two lines, and take the bottles in equal amounts from each line so long as a surplus of bottles is presented by each line.

Our invention will be understood from a study of the accompanying drawings which illustrate the invention, by way of example, as embodied in a machine constructed for the purpose of packing glass bottles. In these drawings:

Fig. 1 is a plan view of the machine. The bot-

tiles enter at the rear end, which is at the right; the front of the machine where the operator stands is at the left;

Fig. 2 is a side elevation taken from the right hand side;

Fig. 3 is an enlarged plan view showing the details of the construction of the end of the machine at which the bottles enter;

Fig. 4 is a side elevation of the apparatus shown in Fig. 3 viewed from the left hand side of the machine;

Fig. 5 is a transverse vertical section taken on line 5—5 of Fig. 3;

Fig. 6 illustrates a detail and is a vertical longitudinal section taken on line 6—6 of Fig. 3;

Fig. 7 is an enlarged view of the charge-forming and packing mechanism and is a longitudinal vertical section taken on the broken line 7—7 of Fig. 9 looking in the direction of the arrows. The 20 carton is shown in dotted lines in the elevated position ready to receive a charge of bottles;

Fig. 8 is an enlarged transverse vertical section taken on line 8—8 of Fig. 7. The carton is still elevated and the charge of bottles is about to be 25 moved into position to drop into it;

Fig. 9 is an end elevation of the front end of the machine, which is at the left in Figs. 1 and 2. The carton has received the charge of bottles and been lowered into position to be ejected from the 30 machine;

Fig. 10 is an enlarged side elevation of the charge-forming and packing mechanism taken from the left-hand side of the machine. A fresh carton is shown in position to be elevated to receive the next charge of bottles;

Fig. 11 is a horizontal section taken on line 11—11 of Fig. 7 to show in plan view the packing mechanism including the devices for directing the individual bottles into their respective cells 40 or compartments and simultaneously straightening or positioning the partitioning devices. Certain parts are omitted for the sake of clearness;

Fig. 12 is a vertical longitudinal section taken on line 12—12 of Fig. 11 showing the bottle directing chutes and their fingers for directing the individual bottles into their respective compartments and simultaneously straightening or positioning the partitioning devices within the carton;

50 Figs. 13 and 13a are enlarged and somewhat diagrammatic plan views of a portion of the packing mechanism of Fig. 11 illustrating the manner in which the bottle directing chutes accommodate rows of bottles of different lengths 55 due to variation in bottle diameter, illustrating how the guide plates of the charge-forming mechanism are aligned vertically with the bottle-supporting rails thereby causing the bottles to drop between the rails and engage the centralizing guides in so doing;

Fig. 14 is a fragmentary vertical transverse section, that is, a section at right angles to that of Fig. 12;

Fig. 15 is an enlarged diagrammatic plan view 65 similar to Figs. 13 and 13a showing a single row of bottles all of which are somewhat larger in diameter than the average, thereby making a row of greater than average length;

Fig. 16 is an enlarged side elevation of a centralizing guide;

Fig. 17 is a view of the centralizing guide in section taken on line 17—17 of Fig. 16;

Fig. 18 is a horizontal section taken on line 18—18 of Fig. 12 showing the details of the 75 mounting of the centralizing guide;

Fig. 19 is a perspective view of a notched bracket plate for supporting the edges of the centralizing guides;

Figs. 20 to 24, inclusive, illustrate a packing mechanism provided with a modified form of 5 centralizing guides, these figures corresponding respectively to Figs. 11 to 15, inclusive;

Fig. 25 is an enlarged view similar to Fig. 16 of the modified centralizing guide and its mounting;

Fig. 26 is an enlarged side elevation of the centralizing guide shown in Fig. 25;

Fig. 27 is a horizontal section taken on line 27—27 of Fig. 25 to assist in illustrating the manner of supporting and replacing one of the 15 modified centralizing guides;

Fig. 28 is a fragmentary section taken on line 28—28 of Fig. 25 showing the rounded sloping centralizing edge of the modified guide;

Fig. 29 is a plan view similar to Fig. 1 but 20 showing a modified form of the apparatus for converging the two lines of bottles entering the apparatus;

Fig. 30 is a sectional view taken on line 30—30 of Fig. 29;

Fig. 31 is a sectional view taken on line 31—31 of Fig. 29;

Fig. 32 is a sectional view taken on line 32—32 of Fig. 29;

Fig. 33 is a side elevation of the left hand portion of the apparatus as shown in Fig. 2 with certain parts omitted and for the purpose of illustrating a modification of certain details; and

Fig. 34 is a transverse vertical section similar to the lower part of Fig. 8 for the purpose of illustrating a modified carton supporting table.

Referring now to the accompanying drawings, and first to Figs. 1 and 2, the bottles enter the machine standing upright in two lines, or rows, 1 and 2, each row usually coming from a labelling 40 machine. The two lines of bottles are received upon a wide belt 3 being maintained in line by suitable guide rails 4, 5 and 6.

The two rows are combined into a single row 7 between guide rails 8 and 9 by means of a bottle switching mechanism, indicated generally by reference numeral 10. A distributing mechanism indicated generally by reference numeral 11 rearranges the single row of bottles into four rows 12, each of these rows receiving an equal 50 number of bottles.

The bottles are maintained in line in these rows by means of guide rails 13. They travel on the belt 3 through the switching device 10, and the dividing mechanism 11 and are delivered by this belt to the charge-assembling and packing mechanism indicated, as a whole, by numeral 14. The distance along belt 3 between the dividing mechanism 11 and the apparatus 14 affords a storage area for bottles arranged in rows ready to be delivered to the charge-assembling and packing mechanism, so that a full charge will be available as often as the assembling mechanism is ready to receive a fresh charge. The belt 3 slides beneath the bottles whenever it is necessary for the bottles to pause before being admitted to the switching device 10 or the charge-assembling and packing mechanism 14.

As shown in Fig. 1, the parts of the charge-assembling and packing mechanism 14 are in 70 position ready to receive a charge of bottles, and as soon as each of the four rows receives its full complement of six bottles each, and a carton 15 has been placed in the machine by the operator and elevated to the position shown in Fig. 7 by 75

depressing the foot lever 16, the charge of bottles drops vertically into the carton from the elevation of the surface of belt 3. The weight of the bottles in the carton on the carton supporting table 17 causes the table to descend to its original position, as shown in Figs. 2 and 9 and the carton moves by gravity to the right, as shown at Fig. 9 onto a roller conveying table 18 by which the carton is carried to the next operation, usually to an automatic carton closing machine.

Having thus briefly outlined the operation of the machine, we will now proceed to a description of its various parts in detail as to both their construction and operation.

The apparatus is driven by an electric motor 19 shown in Fig. 1 which is belted to a reduction gearing 20, the slow speed shaft of which is provided with two sprockets 21 and 22. The wide belt 3 previously referred to is carried by a driving drum or roll 23 near the front end, and by a similar but smaller roll 24 at the rear end of the machine. These supporting rolls are appropriately journaled in the machine frame which comprises two side bars 25 extending substantially from end to end of the machine, and four upright posts. The posts are tied together near their bases by longitudinal members 27. Belt 3 is driven continuously by means of roller 23 so long as the machine is in operation. The shaft of roller 23 is provided with a sprocket 28 which is connected with sprocket 22 on the reducing gearing shaft by means of a chain.

The upper reach of wide belt 3 is maintained level by parallel supporting bars 29, shown in section in Fig. 5, which extend between the belt supporting rollers 24 and 23. At the rear end of the machine immediately below roller 24, there is arranged an adjustable tension roller 30 and an idle roller 31 around which the lower reach of belt 3 passes, and by means of appropriate adjusting screws 32 the tension roll 30 can be adjusted so as to maintain the desired tension on the belt.

Referring now particularly to Figs. 3, 4 and 5, and the right hand ends of Figs. 1 and 2, there is here illustrated the switching mechanism 10 by means of which the bottle packing machine is enabled to receive its supply of bottles from two sources.

The bottles enter the packing machine by the lines 1 and 2, each ordinarily leading from a labelling machine, and are carried forward by belt 3 between the rails 4, 5 and 6 which are appropriately suspended above the belt 3 from a horizontal bar 33. These rails, and also rails 8, 9 and 13 which subsequently guide the bottles, are made in spaced upper and lower sections as may be seen in Fig. 2 so that the labels of the bottles will not be marred by contact with them.

As the bottles are carried forward by the belt, they are received five at a time from each of rows 1 and 2 in a pair of simultaneously actuated switching channels 34 and 35 which are oscillated periodically, as will presently be described, to deliver their respective groups of five cans each successively to form a single row which continues its advance between the rails 8 and 9.

The switching channels 34 and 35 are alike in construction, and each comprises a pair of vertical plates (36 and 37 for channel 34, and 38 and 39 for channel 35) fixedly suspended from inverted U-shaped members 40 and 41 respectively. These U-shaped members are fixed to the lower ends of vertical shafts 42 and 43 which are

mounted for oscillation in long bearing bosses 44 on a transverse supporting member 45 which is mounted upon the upper ends of posts 26.

The switch channels 34 and 35 are oscillated by the following mechanism under the control of the cans advancing in lines 1 and 2. A cam shaft 46 is journaled in the frame members 25 close to the two posts 26 at the rear end of the machine. This shaft is driven by means of a chain 47 and suitable sprockets from the shaft of roller 24. Keyed near the opposite ends of shaft 46 is a pair of cams 48 and 49, the cam surfaces of which are arranged 180° apart so that when the cam shaft is rotated the switching channels 34 and 35 will be oscillated in unison in one direction or the other by means of the levers and linkage shown in Figs. 3, 4 and 5.

The connecting mechanism just referred to includes cam followers 50 and 51 which are arranged on cam follower levers 52 and 53 mounted at the lower ends of two vertical shafts 54 and 55. These shafts are pivoted as shown in Figs. 4 and 5 in suitable brackets 56 and 57 on the frame of the machine. The upper part of these shafts communicate their motion to the switch channels 34 and 35, while the mechanism shown near the lower portions of these shafts (and to the right, as viewed in Fig. 4) is that by which the oscillation of the switch channels is controlled.

These two mechanisms are identical on the two opposite sides of the machine. That is to say, the mechanism for actuating switch channel 35 by means of cam 49 is identical with that for actuating switch channel 34 by cam 48. Only one set of these mechanisms will be described.

The mechanism adjacent the upper end of shaft 54 for communicating the oscillation of this shaft to the switch channel 34 comprises a short lever 58 which is fixed to shaft 54, and a longer lever 59 which is loose on this shaft. A link 60 is pivoted to the outer end of this long lever and to inverted U member 40 of switch channel 34.

Shaft 54 is oscillated in one direction by means of the cam elevation 61 acting on cam follower 50, and in the opposite direction by means of a helical spring 62 which is attached at one end to the frame of the machine and at the other end to an extension 63 of cam follower lever 52. The motion of short lever 58 is communicated to lever 59 in order to oscillate the switch channel 34. In the direction of movement under the actuation of spring 62 this connection is a positive connection, whereas in the opposite direction of movement under the coaction of cam elevation 61 and cam follower 50, it is a yielding connection. In this way the switch channels 34 and 35 are yieldingly actuated in both directions so that should any jamming of bottles occur at the throat of guide rails 8 and 9, no damage would occur.

The connection between short lever 58 and long lever 59 includes a block 64 which is pivoted at 65 to the outer end of short lever 58, and which, under normal conditions, engages a somewhat similar block 66 which is fixed to the lower surface of long lever 59. These two blocks are held in engagement with one another by means of a helical spring 67 which is mounted upon a threaded rod 68, this rod being secured to the pivoted block 64 and extending through a suitable aperture in block 66 and being provided at its outer end with a nut 69. This spring keeps the blocks in contact to provide the posi-

tive actuation in one direction and provides a yielding connection between the blocks in the opposite direction of movement.

A control mechanism near the bottom and to the right of vertical shaft 54 as viewed in Fig. 4 controls the actuation of switch channel 34 by cam disc 48 by controlling the extension 63 of cam follower lever 52. Extension 63 is provided at its outer end with a latch block 70 adapted to be engaged by the end of a latch lever 71 which is pivoted loosely on a vertical shaft 72 that is carried upon a bracket member 73 secured to the machine frame. When in the position shown in the drawings, latch bar 71 prevents the oscillation of switching channel 34 under the influence of spring 62 when, due to rotation, the inner dwell 74 on cam 48 and cam surface 61 tend to permit cam follower 50 to move into engagement with the outer dwell 75. On each revolution of cam 48, however, the inner dwell 74 contacts with cam follower 50 sufficiently to move the parts slightly so as to shift latch block 70 out of engagement with the end of latch lever 71 for a purpose which will presently appear.

Latch bar 71 is controlled by the bottles within the switch channel 34 and for this purpose a control lever 76 is provided. This lever is pivoted on shaft 72 above latch bar 71, and has at its inner end a thin adjustable bottle engaging stop plate 77 which is positioned close to the end of guide rail 8 and is engaged by the center of the foremost bottle within switch channel 34. The pressure of the bottles within the switch channel against the stop plate 77 under their friction with the moving belt 3 tends to cause control lever 76 to be moved forward against the tension of a spring 78 against an adjustable stop 79 mounted on brackets 13. When such movement of control lever 76 occurs, it places under tension a spring 80 which connects the tail portion 81 of this lever with the latch lever 71, one end of spring 80 being connected to tail portion 81, and the opposite end to a pin 82 which extends upwardly from lever 71 through a slot in tail portion 81. Then upon the next rotation of cam 48, when cam follower 50 rides up on inner dwell 74 and thereby shifts the parts sufficiently to cause latch block 70 to release latch lever 71, this lever is actuated by the tension of spring 80 just referred to, to the left, as viewed in Fig. 3 so as to bring the end of latch lever 71 out of the path of latch block 70. Following this, as soon as the cam 48 has rotated 180°, or, in other words, to the point where the cam follower 50 commences to roll off from the inner dwell 74 along cam surface 61 toward the outer dwell 75, the vertical shaft 54 is thereby oscillated and thus causes the oscillation, or shifting, of the switching channel 34 from the position shown in Fig. 3 to its opposite position whereby the five bottles therein are permitted to be advanced by belt 3 into the space between the guide rails 8 and 9.

As this motion of switching channel 34 takes place, it is to be noted that the left-hand end of plate 37 swings into the path of the oncoming bottles in line 1 and prevents their advancement, while the right-hand end of plate 36 moves into alignment with guide rail 8, thereby shifting the foremost bottle laterally out of engagement with the stop plate 77 so as to allow the five bottles in the channel 34 to advance. With this same movement, switching channel 35 moves in the reverse direction and plate 38 of that switch-

ing channel, which has theretofore occupied the position shown in Fig. 3 wherein it holds back the bottles advancing in line 2, is now shifted into alignment with guide rail 5, thereby permitting bottles from line 2 to advance into channel 5 35. This movement also brings the center of the forward, or right-hand, end of channel 35 opposite the stop plate 77 of the control lever 16a, of the oscillation control mechanism of switching channel 35.

It will be understood, by means of the mechanism just described, the bottles are delivered in groups of 5 taken alternately from the feed lines 1 and 2 into a single line which is formed between the guide rails 8 and 9. This single line 15 of bottles is advanced by the belt 3 to the redistributing mechanism, indicated generally by reference numeral 11 and shown in Figs. 1, 3 and 4. This mechanism comprises 3 deflectors 83, 84 and 85 of similar construction and actuated by 20 the bottles so that successive bottles shift the deflectors to cause the bottle immediately following to be diverted into a different path. Thus, when the first bottle engages the deflector 83, it will be directed into the channel 86, and as the 25 bottle moves into this channel, it will cause the deflector 83 to oscillate about its shaft 87 and shift the point of the deflector onto the opposite side of this shaft from that shown in Fig. 3, so that the next bottle following will be diverted 30 into the channel 88. Similarly deflectors 84 and 85 divert the bottles approaching from channels 86 and 88, respectively, into channels 89, 90, 91 and 92 formed between the guide rails 13.

Each of the deflectors 83, 84 and 85 is of particular construction in order to properly operate upon bottles standing upright and being advanced by means of a belt such as belt 3. This construction is illustrated in Figs. 4 and 1.

A superstructure is built above belt 3 comprising two side members 93 and 94 which are secured to the side bars 25 of the machine frame. Connecting the upper ends of these side members 93 is a horizontal plate, or casting 95. The deflectors 83, 84 and 85 are carried by this casting, 45 and for this reason, three vertical extensions 96 project downwardly from the casting 95.

All three of the deflectors 83, 84 and 85 are alike, and consequently only one will be described in detail. Deflector 83, for example, comprises 50 two narrow deflecting members 97 and 98 which are mounted upon a vertical shaft 99. The deflecting members 97 and 98 are spaced apart on this shaft sufficiently to avoid contact with the labels on the bottles so as to avoid the possibility 55 of their being damaged. Shaft 99 extends downwardly through one of the projections 96 to a point close to the surface of belt 3 in order to support deflector 98 below the label position.

It is important that the deflecting members 97 and 98 respond easily to the pressure of the individual bottles to swing from one side to the other, and yet the resistance to this swinging movement tends to be very considerable because of the pressure which must be exerted by the deflector 65 against the bottles to slide the bottles sidewise on the belt 3, and because the shaft 99 must be suspended from a considerable distance above the belt. The desired free movement of the deflectors is provided by making shaft 99 extend well above 70 the belt 3 and providing a long bearing for this shaft in one of the projections 96. In this way, the tendency for the shaft 99 to bind due to the pressure of the bottles transmitted to the lower end of the shaft is eliminated, and the deflectors 75

97 and 98 will swing easily to one side or the other.

It will be understood that the deflectors 97 and 98, indicated generally by reference numerals 83, 5 84 and 85, are arranged to have only two stable positions. This is accomplished by means of a light helical spring 100 at the top of each of the shafts 99, one end of which is fixed to the frame, and the other to an eccentrically mounted pin 101. The two positions are determined by means of a pair of adjustable stops 102.

The bottles are carried forward from the redistributing mechanism 11 by means of belt 3 in the four lines 89, 90, 91 and 92 between the 15 guide rails 13 to the charge-assembling and packing mechanism 14. The bottles as they reach the end of belt 3 over driving roll 23 are received upon a series of narrow supporting rails 103 (see Figs. 7, 8, 9, 11 and 12) which consist of thin metal 20 plates mounted on edge in spaced parallel relation between a pair of transverse supporting bars 104 and 105. Bar 104 is secured to extensions 106 of the side frame bars 25 which project beyond the two posts 26 near the front end of the 25 machine. These extensions 106 support the entire charge-assembling and directing mechanism. Bar 105 is secured by collared bolts in spaced relation to a cross member 105a which is mounted on the outer ends of extensions 106. The ends 30 of rails 103 are curved at 107 to bring their tips close to the surface of belt 3 as it passes around roller 23, as shown in Figs. 7 and 12 in order that the bottles may slide smoothly from the belt onto the rails.

35 The guide rails 13 terminate at a point vertically above the supporting bar 104 at the entrance to the charge-assembling mechanism. Beyond this point the bottles pass between a series of parallel spaced guide plates or slides 108 of the 40 charge-shifting frame indicated generally by reference numeral 109 by means of which the bottles are supported in upright position on the rails 103 and the alinement of the bottles is preserved. The height of guide plates 108 is preferably somewhat greater than the height of the 45 bottles, and the spacing of the guide plates is the same as the spacing of guide rails 13, the plates when in the charge-receiving position, as shown in Figs. 1, 7, 9 and 10, being in alinement with 50 these guide rails.

The charge-shifting frame 109 comprises the 55 guide plates or slides 108, a pair of horizontal parallel rods which extend crosswise of the machine and four upright levers 111. The plates 108 are suspended from the two cross rods 110 by suitable hangers 112 by means of which the plates are carried in firmly fixed relation upon the rods. The four levers 111 connect with rods 110, constituting a parallelogram linkage by 60 means of which the charge-shifting frame may be shifted laterally with respect to supporting rails 103. From the position shown in Fig. 8 where the guide plates 108 are in alinement with guide rails 13 and the supporting rails 103 are 65 opposite the centers of the spaces between the guide plates 108, to the position shown in the fragmentary view in Fig. 14 in which the guide plates 108 are in alinement with rails 103 thereby causing the charge of bottles to descend by gravity between rails 103 into the carton 15.

The rails 103 thus form between them a plurality of chutes, each of which is subdivided, as will be later described, to form directing chutes for the individual bottles to direct them into their respective cells. Each plate 108 at the left

of a row of bottles, as viewed in Fig. 8, acts as a slide, or pusher, to push the row of bottles which has been transported into the range of the pusher along one of the feeding rails 103, laterally of its supporting rail to deliver it to the chute. Each plate 108 at the right of a row of bottles acts to check the movement of the bottles therein as they are moved laterally by the adjacent plate 108 at the left acting as a pusher.

The two levers 111 on the right-hand side of the machine are pivoted upon a horizontal shaft 113 which is carried in brackets 114 on the machine frame. On the left-hand side the two levers 111 are fixed to a horizontal shaft 115 (see Fig. 10) and the shifting of the shiftable frame 15 109 is accomplished by rocking this shaft 115 as will presently be described. Shaft 115 is journaled near its right-hand end, as shown in Fig. 10, in a boss 116 projecting from a bracket 117 which is bolted to the machine frame at the 20 outer end of extension 106, as shown in Figs. 10, 9 and 7. At its left-hand end, as viewed in Fig. 10, shaft 115 is journaled in a bracket 118 also bolted to frame extension 106. A collar 119 is fixed to shaft 115 adjacent the right-hand side of the 25 bracket 118 to prevent the shaft from shifting longitudinally in one direction. The parts, as shown in Fig. 10 close to the left-hand side of bracket 118, which will presently be described, prevent the shaft from shifting in the opposite 30 direction.

The description of the mechanism for automatically rocking shaft 115 for the purpose of actuating the charge-shifting frame 109 to cause the charge of bottles to drop between the 35 rails 103 into the carton 15 will be taken up presently, but before this, the mechanism by which the operator of the machine raises and lowers the successive cartons to and from the charge-receiving position shown in Fig. 7 will be 40 described.

The operator first places in the carton about to be placed in the packing machine a set of partitioning devices which divide the lower part of the carton into a plurality of square cells, 45 pockets, or compartments, each adapted to receive a single bottle. In the machine chosen for illustration the charge of bottles consists of four rows of six bottles each so that the partitioning device divides the carton into 24 bottle compartments. This partitioning device usually consists of crossed strips of corrugated board suitably slitted from opposite edges to permit the assemblage of the strips, and reference numeral 120 indicates the longitudinal strips (Fig. 8) of this 50 partitioning device, while numeral 121 indicates the cross strips (Fig. 12), each being shown in section. The operator places the thus prepared carton temporarily on the shelf 122 with its end against a positioning bar 123 which is adjustably supported, as shown in Figs. 7 and 10. At the proper time the operator slides the carton by hand off from shelf 122 onto the carton-supporting table 17. The position of the carton is shown in dotted lines in Figs. 9 and 10.

Supporting table 17 is a roller table having a plurality of rollers 124 mounted in a frame 125. The side of the carton is positioned against a stop member 126 carried on the supporting table 17. At first the carton will not lie quite flat on the rollers 124, as indicated in Fig. 9, because of the presence of a single tilting roller 127 which is mounted on stationary supports 128 secured to the machine frame, but as soon as the table 17 is elevated slightly the carton will assume 75

an upright position. The positioning bar 123 and stop member 126 serve to locate carton 15 beneath the charge-directing mechanism, which is indicated generally by numeral 129, so that when the carton is elevated to the position shown in Fig. 7, the charge-directing mechanism will be properly received within the mouth of the cartons, and the individual bottle-directing chutes 130, to be later described, will have their lower ends inserted respectively in the 24 bottle pockets, or cells.

Carton-supporting table 17 is arranged with its frame 125 mounted upon the upper end of a central supporting post which is slidable vertically in a cylindrical member 132 which is bolted to a cross member 133 mounted upon the front ends of the frame side bars 25. Supporting table 17 is counterbalanced by means of a cylindrical weight 134 (Figs. 2, 8 and 9) which is adjustably mounted upon a bar 135 which is pivoted at 136 to the frame of the machine and connected at its front end by means of a chain 137 and a pin 138 to the lower end of the vertically movable supporting post 131.

The counterbalance weight 134 is adjusted so that when the carton has received a charge of bottles, the weight of the bottles will just overbalance the counterweight and cause the table 17 to return to its lowermost position. Then the carton will be tilted, as shown in Fig. 9 because of the elevation of the tilting roller 127 above the rollers 124 of table 17. This tilting causes the filled carton to move by gravity onto the roller conveying table 18 by which the carton is carried along, for example, to a carton closing machine.

In order to retain the empty carton supporting table 17 in its lowermost position, a bar 139 is provided. This is provided with a latching shoulder 140 which engages the top of a latch plate 141 which is mounted upon the supporting table frame 125. Latch 139 is fixed upon a cross shaft 142 which is pivoted on suitable brackets secured to the machine frame, and the latch is biased into engaging position with latching shoulder 140 by means of a spring 141. The latch is released by the operator by means of foot lever 16 which is also fixed to shaft 142. In order to retain the latch in its released position during the raising and lowering of carton-supporting table 17, latch 139 is provided with an extended head 144 which engages the front surface of a latching shoulder member 140.

The mechanism for automatically actuating the charge-shifting frame 109 for causing an assembled charge of bottles to be dropped through the charge-directing mechanism 129 into carton 15 while in the raised charge-receiving position shown in Fig. 7 will now be described. This operation takes place whenever there is a full charge of bottles in the charge-shifting frame 109 and a carton 15 has been raised to the elevated position of Fig. 7. The mechanism of the present invention provides for automatically shifting the suitable frame 109 as often as both of these two conditions are met, but not otherwise.

Referring to Figs. 7 to 10, inclusive, the actuation of charge-shifting frame 109 is accomplished by the rotation of a disc cam 145, the cam follower of which 146 is at the lower end of a lever 147 which is loosely mounted upon rock shaft 115 but which is provided with an extension 148 which is connected to rock shaft 75 115 by means of a one-way-yielding connection

149. The shiftable frame 109 is moved in one direction by the disc cam 145 and in the opposite direction by means of a strong helical spring 150 which is attached to the upper end of extension 148 and secured at its opposite end to a bracket fixed upon the machine frame. The one-way-yielding connection 149 is similar to the yielding connection 64-69 described above in connection with the operation of the switching channels 34 and 35 of the bottle-switching mechanism 10. It comprises a rod 151 carrying a helical spring 152, the rod being threaded into a suitable boss on the extension 148 and passing loosely through a block 153 pivoted at the outer end of a lever 154 which is fixed upon rock shaft 115.

Lever 154 is fixed to this shaft by a releasable clamp 155 to enable the guide plates 108 to be adjusted relative to the supporting rails 103. The shifting frame 109 is moved to the right, 20 as shown in Figs. 8 and 9, by means of spring 150 to cause the charge of bottles to be shifted so as to drop through the directing chutes 130 into the carton. It is moved to the left by means of cam 145 which actuates rock shaft 15 25 in this direction of movement through the spring 152. In case of a jamming of bottles in either direction of movement, no damage thereto will occur because of this spring actuation in both 30 directions of shift. The shifting movement of frame 109 to the right under the influence of spring 150 is limited by means of a stop lever 156 which is adjustably secured to rock shaft 115 and whose outer end engages the upper edge 35 of frame extension 106.

The disc cam 145 for actuating the charge-shifting frame 109 is mounted upon a shaft 157 which extends crosswise of the machine and is driven by means of a sprocket 158 which is connected by a suitable chain with sprocket 21 of 40 the reducing gearing 20. Cam 145 is therefore rotated continuously while the machine is in operation.

The mechanism for controlling the actuation of the charge-shifting frame 109 by cam 145 when 45 there is a full charge of bottles within the shifting frame and the carton is in proper position with respect to the charge-directing mechanism 129 is located at the front end of the machine and is therefore seen in side view in Fig. 9. It is 50 shown in end view in Fig. 10 and in section in Fig. 7. Fixed upon the extreme outer or front end of rock shaft 115 is a latch arm 159. This latch arm is in the horizontal position, as shown in Fig. 9 when the charge-shifting frame 109 is 55 in the position shown in this figure, or, in other words, in the position in which its guide plates 108 are in alignment with the rails 13 so as to receive between them the four rows of bottles which are being advanced toward them by the wide belt 3. 60 Latch arm 159 is held in this horizontal position by a latch lever 160 which extends vertically downward from a latch lever shaft 161 which is arranged crosswise of the machine adjacent the extreme end of the passageways formed between 65 the guide plates 108. This shaft is rockably supported at the upper ends of brackets 117 previously referred to. Latch arm 159 and latch lever 160 are provided with replaceable hardened steel latch blocks, as indicated in Figs. 7 and 9, the 70 latch block on the latch lever 160 engaging beneath the side of the latch block on arm 159. Latch lever 160 is mounted loose upon latch lever shaft 161, and the manner of its actuation to release latch arm 159 will presently appear. 75

Alongside of latch lever 160 and clamped to shaft 161 is an arm 162, and near the opposite ends of shaft 161 are two short and nearly horizontal arms 163, each secured in fixed position on this shaft. Extending between these two short arms 163 are a hardened steel latch bar 164 and a stop bar 165. These are held in position by cap screws 166 and are suitably spaced apart by means of collars. A helical spring 167 which is connected between the frame and a pin at the outer end of arm 162 rocks the shaft 161 and biases the short arms 163 and the latch bar 164 upwardly.

Latch bar 164 is held down against the tension of spring 166 by a series of latches 168 and 168a, latches 168 being bottle-actuated and latch 168a being actuated by mechanism to be described. These are each hardened steel blocks engaging the upper corner of latch bar 164. Each latch is mounted at the upper end of a latch lever 169, there being one lever and latch for each of the rows of bottles between the guide plates 108 of the shiftable frame 109 and one latch lever 169a, which is actuated through the elevation of the carton supporting table 17 to its uppermost position. Latch levers 169 and 169a are pivoted loosely upon a shaft 170 mounted between the brackets 111. Each of the latches 168 at the upper ends of these latch levers is held in engagement with the latch bar 164 by the tension of a light helical spring 171 which is arranged to resist the pressure of the foremost bottle of each row against the lower ends of latch levers 169. Adjustable screws 172 are arranged at the lower ends of the respective levers 169 to be engaged by the bottles. After the bottles strike these screws and swing the levers 169, the further advance of the bottles is prevented by means of stops 173 of rubber, or other suitable material, located on an adjustable stop bar 174 mounted upon the frame of the machine close to the bottoms of the bottles.

Latch lever 169a, which is controlled by the movement of the carton-supporting table 17 to its uppermost position, is actuated by means of a link 175 which is pivoted at one end to the lower end of latch lever 169a, as shown in Fig. 10, and at its opposite end to a bell crank lever 176. This bell crank lever is pivoted to the frame of the machine, and its second arm is provided with a pin 177 which is arranged in the path of the upper end of a vertical bar 178 which is mounted in fixed position and extends upwardly from the rear frame of carton-supporting table 17 (Figs. 7, 9 and 10).

The friction of the bottles on the wide belt 3 between the guide rails 13 pushes forward the bottles ahead of them on the supporting rails 103 between the guide plates 108 of the charge-shifting frame 109 and causes these bottles to be advanced against the stops 173 of the stop bar 174. In moving against these stops, the foremost bottles of each row trip their respective latch levers 169, thereby releasing their latches 168 from the latch bar 164. When the operator has placed a carton upon the supporting table 17 and tripped latch 160 by means of foot lever 16, the counterweight 134 causes the supporting table to rise until the mouth of the carton thereon surrounds the charge-directing mechanism 129, and at this point the upper end of vertical bar 178 engages pin 177, rocks bell crank lever 176 and through link 175 actuates or trips the fifth latch lever 169.

Now that all five of the latches are released from latch bar 164, it is free to move upwardly

under the tension of spring 167 connected at the end of arm 162. The tendency of arm 162 to move under the tension of spring 169 is communicated to latch lever 160, which is loose on shaft 161, by means of a pin 179 (Figs. 9 and 10) which projects laterally from each side of arm 162. The left-hand end of this pin, as viewed in Fig. 9, passes through a slot 180 in a link 181 which is pivoted at its lower end to arm 160. Pin 179 engages the lower end of this slot and urges arm 160 to the left, as viewed in Fig. 10, and to the right, as viewed in Fig. 7, thereby tending to release the latch arm 159. But the friction between the latch block of arm 160 and latch arm 159 is too great to be overcome by spring 167. 15

When, however, the disc cam 145 rotates from the position shown in Fig. 10, to the point where one end of its cam formation 182 (Fig. 10) engages the cam follower roller 146, it moves lever 147 and rock shaft 115 just sufficiently to lift 20 latch arm 159 out of engagement with the upper end of the latch block of latch lever 160. This occurs on each rotation of cam 145, latch arm 159 dropping back to engagement with the latch block of latch arm 160 when the cam has rotated 25 180° and cam formation 182 disengages the cam roller 146, unless, as described above, all of the five latches 168 and 168a have released latch bar 164. In that event, as soon as cam formation 182 engages roller 146 and causes the latch arm 30 159 to lift away from the latch block of latch lever 160, the tension of spring 167 acting through pin 179 and link 181 immediately shifts the block of lever 160 out of the path of latch arm 159. Then, upon the disengagement of cam formation 182 from the cam roller 146, rock shaft 115 is rocked through a full stroke and charge-shifting frame 109 is moved to the right shifting the four rows of bottles off from the supporting rails 103 and causing them to descend 40 through the bottle-directing chutes 130 into the carton 15. 35

As soon as the edge of the latch block of latch arm 159 passes below the upper corner of the latch block of latch lever 160, the upper edge of 45 latch bar 164 is raised above the lower corners of the latches 168 and 168a. The descent of latch arm 159 causes a resetting cam 183 carried by this arm to engage a roller 184 at the outer end of arm 162 and swing this arm outwardly against 50 the tension of spring 167, thereby lowering the latch bar 164 to resetting position below the lower edges of the latches 168. As soon as the bottles drop, the four bottle actuated latches 168 are released and under the tension of springs 171 55 they are returned to their original positions above latch bar 164. As soon as the charge of bottles is deposited in the carton 15 and the weight thereof has commenced to lower the carton supporting table 17, vertical bar 17 releases pin 177 60 of bell crank 176 and through link 175 releases the fifth latch 169a. 60

When cam 145 has completed a half-revolution, the opposite end of cam formation 182 re-engages cam follower roller 146 and rocks rock 65 shaft 115, shifting the bottle-shifting frame 109 back to the position where its guide plates 108 are arranged as shown in Fig. 8 and are in alignment with the guide rails 13 (Fig. 1) to receive a fresh charge of bottles. This raises latch arm 70 159 to its original position and the latch block of latch lever 160 is caused to snap back beneath the same by means of a helical tension spring 185 (Fig. 7). This movement releases resetting cam 183 from roller 184 and spring 167 again 75

urges arm 162 downwardly, thus rocking shaft 161 and causing latch bar 164 to again engage the lower faces of latches 168 and 168a. This completes a cycle of operation of the machine, and the parts are now again in position to receive a fresh charge of bottles and pack it in a succeeding carton.

The preferred form of packing mechanism with which is included devices for separating the individual bottles of each row to accommodate the partitions, and for directing the individual bottles into their respective compartments and simultaneously straightening or positioning the partitioning devices, is illustrated in Figs. 11 to 19, inclusive. The elongated spaces between the respective bottle supporting rails 103 and bounded by the supporting bars 104 and 105 is subdivided into small squares approximately the size of the individual bottles by the plates 187 of centralizing guides 186 to form the bottle-directing chutes 130.

Each of these centralizing guides is composed of a comparatively thick metal plate 187 having a pair of flexible bottle-directing and partition positioning fingers 188 depending therefrom (see Figs. 16 and 17). The thick plates 187 are each provided with a symmetrical V-shaped notch 189 in their upper edges which serves to shift the bottles toward the centers of the directing chutes 130 as they commence to descend, and for this reason the edges of the V-shaped notches 189 are well rounded, as indicated in Figs. 16 and 17, to prevent disfiguring the labels.

The centralizing guides 186 are "floatingly" mounted transversely between the rails 103 and their notched plates 187 are of the same height as these rails. The respective bottle-directing chutes 130 comprise two of these centralizing guides 186 together with the portions of the pair of rails 103 included between them and four of the flexible bottle-directing and partition-positioning fingers 188, two for each chute being secured to the lower edges of the two notched plates 187 of the centralizing guides and two of them being secured to the edges of the rails 103 midway between the centralizing guides.

These flexible fingers 188 extend downwardly as may be seen in Fig. 12 to a point somewhat below the upper edges of the crossed strips 120 and 121 forming the partitioning devices. Hence as the bottles descend through the directing chutes 130 they are first guided by the notched plates 187 of the centralizing guides toward the centers of the respective chutes, and are thereafter directed into their respective cells or compartments in the case below by means of the flexible fingers 188 which at the same time shift the partitioning devices 120-121 as may be necessary to accommodate all of the bottles of the charge and to prevent the bottoms of the bottles from jamming against the upper edges of the partitioning devices.

Only three flexible fingers 188 are necessary along the rows forming the sides and ends of the charge inasmuch as thin plates 190 and 191 are provided at the sides and ends of the packing mechanism for the purpose of forming a funnel-like member to receive the mouth of the case or carton 15, and these also function as guiding fingers for the bottles of the outside rows.

The flexible fingers 188 are preferably secured to the notched plates 187 of the centralizing guides 186 and to the lower edges of the rails 103 in the manner shown in Figs. 16, 17 and 12. That is to say, referring, for example, to Figs.

16 and 17, the pair of fingers 188 is made of a single strip of flexible resilient metal such as spring steel which is formed to the shape shown in Fig. 17, and the upper end is then snapped over a horizontal projection 192 provided on the lower edge of plate 187 which is reduced in thickness, as shown in Fig. 17 so that the outer surfaces of the upper ends of fingers 188 are flush with the opposite surfaces of plate 187. By means of this construction, the flexible fingers 188 may be quickly replaced, if necessary, without removing the notched plates 187 from the apparatus.

The centralizing guides 186 are supported between the rails 103 by means of notched bracket plates 193 (Fig. 19) which are riveted to the rails 103 as shown in Fig. 18. Shoulders 194 on the opposite side edges of the notched plate 187 rest in the bottoms of notches 195 at the top of the bracket plates 193, and projections 196 and 197 fit within the lower notches 198 in the bracket plates.

One of the difficult problems in making a bottle packing machine of the type of the present invention operate satisfactorily is that of providing for variation in the diameter of bottles of a given nominal size, and one of the features of the present machine contributing largely to the successful handling of bottles of varying diameter is this centralizing guide 186 and the manner in which it is mounted. The V-notched plates 187 of this guide are of such a thickness as to be substantially rigid and the notches 195 and 198 in the bracket plates 193 are of sufficient width to give the centralizing guides a considerable freedom of movement (a "floating" movement) in a direction parallel with the rails 103, but plates 187 are held against any substantial movement at right angles. In practice the notched guide plates 187 are approximately $\frac{1}{8}$ in. in thickness and are preferably made of a corrosion resisting metal such, for example, as copper or bronze, and the notches 195 and 198 are approximately $\frac{3}{8}$ in. in width, thus giving the centralizing guides a freedom of movement of $\frac{1}{8}$ in. in either direction from the central position.

The lengths of the four rows of six bottles each forming the charge within the packing mechanism 14 will change with the usual variations in bottle diameter. As the left-hand end of each row is always stopped at the same point by the rubber stop cushions 173 (after engaging the adjustable screws 172 and moving the latch levers 169 to released position) the position of the sixth bottle in a given row, that is, the last bottle to enter the packing mechanism, will vary with the changes in size of the bottles ahead of it. The bottles in single row N shown in dotted lines in Figs. 11 and 12, and in row N in Fig. 13a, are assumed to be of normal or average diameter and hence these rows are of average length. The row of bottles S in Fig. 13 is assumed to be composed of bottles which are smaller in diameter than the average and hence the length of this row is shorter than the average. In Fig. 15, the row L is supposedly composed of bottles which are larger than the average and represents the maximum length of row which the machine is capable of handling. It will be understood that in actual practice the various sizes of bottles are mixed together so that each row will usually contain some bottles smaller than average and some bottles larger than average, so that the row N is intended to

represent a row of average or normal length, but will usually be composed of bottles of different sizes.

The separating of the individual bottles of each row from one another in order to accommodate the partitioning strips 121 and align the individual bottles more or less accurately with their respective cells C, C₁, C₂ is done by the V-notched plates 187. In order to reduce the maximum distance of shift of any bottle in a given row to a minimum, the stop supporting bar 174 is adjustably mounted as indicated in Figs. 11 and 12. For this purpose the bar is mounted upon two narrow angle brackets 199 by means of a pair of screws 200 which pass through elongated slots 201 in bar 174 (see Figs. 9, 11 and 12).

Stop bar 174 carrying the rubber stop cushion buttons 173 might be so adjusted that when a row of average size bottles N is in the position shown in Figs. 11 and 12, that is, with the left-hand bottle against its stop button, the line of contact between the center two bottles B of the row is vertically above the center of center guide plate 187 when this guide plate is at the center of its supporting slots or sockets 195 (see Fig. 18). The lines of contact between the two bottles B and their neighbors B₁ on each side of the center is slightly out of vertical alignment with the centers of the separating plates 187 beneath, while the lines of contact between the bottles B₁ and their neighbors B₂ is still further out of alignment with the respective separating plates 187 beneath. These differences of alignment indicate the extent of movement of the respective bottles necessary in order to separate the bottles and bring them individually into vertical alignment with their respective directing chutes 130 in order that they may be directed into the cells of the carton.

When the row of bottles is shifted laterally by the movement of guide plates 108 (of the charge-shifting frame 109) to the position shown in Fig. 14, to cause the charge of bottles to descend into the carton 15, the bottles of each row are separated from one another by the camming action of the circular bottoms of the bottles engaging the V-shaped notches 189 of separating plates 187. Plates 187, therefore, effect the separating of the bottles of each row and direct the bottles downwardly into engagement with the flexible fingers 188 by means of which the bottles are guided into their respective cells and at the same time the walls of the cells are deflected, if necessary, by the lower ends of the flexible fingers into their correct positions between the bottles of each row and the bottles of adjacent rows. Inasmuch as the separating plates 187 are mounted so that they can shift in one direction or the other they can take up any position in their supporting slots 195 (Fig. 18) required by the assortment of bottles of varying diameter which happens to be found in each particular row as it is received by the packing mechanism for delivery to the carton.

The approximate positions of these separating plates under various conditions of operation is illustrated in Figs. 13, 13_a and 15, which indicate the approximate distances the respective bottles must be shifted by the notched separating plates 186 under such various conditions. In these figures the bottles shown in dotted lines are in position on top of rails 103, while the bottles shown in full lines have descended into their respective directing chutes 130. That is to say, the V-notched separating plates 187 have effected the

separation between the individual bottles of each row. The approximate relative positions of the bottles with respect to these separating plates in a row N of average size bottles, in a row S of smaller than average bottles, and in a row L of larger than average bottles is here indicated.

From these figures and also from Figs. 11 and 12 it will be understood that it is of importance that the stop cushions 173 be of comparatively narrow width so as to permit the bottles to be moved to the left, if necessary, by the separating plates 187 after the shifting of guide plates 108. The extent of this left-wise movement depends upon the length of the particular row, as shown in Figs. 13, 13_a and 15, and is determined by the assortment of bottles as to sizes in each particular row. This shifting movement of the individual rows of the charge by the charge-shifting frame 109 with its guide plates 108 removes the end bottle of each row laterally from its stop cushion, and as the stop cushions are relatively narrow, they do not interfere with the shifting movement of the bottles which is produced by the separating plates 187.

Referring now to Figs. 20 to 28 of the drawings, there is here illustrated a modified form of packing mechanism in which the "floating" effect of the separating and centralizing devices is accomplished in a somewhat different manner. Instead of providing a separating and centralizing guide of the all-rigid type, such as indicated by numeral 186 of Figs. 16 and 17, a separating and centralizing guide 186_a shown in Figs. 25 to 28, inclusive, is provided. This centralizing device has a rigid portion 202 and a flexible portion 203, and instead of being mounted in notched bracket plates 193, as shown in Fig. 18, is mounted directly on the rails 103_a of the packing mechanism which are provided with suitable notches 204 which are arranged in spaced relation along both the upper and lower edges of the rails. The portions 202 and 203 of the separating and centralizing device are each provided at their upper and lower edges with small projections 205 and 206 adapted to be received within the notches 204 in the rails. Because of the flexibility of the flexible portions 203, these separating devices may be placed in position by springing the flexible portions 203, as indicated in Fig. 27. They may also be removed and replaced, if necessary, in the same manner.

The rigid portion 202 of these centralizing and separating devices may conveniently be made of a piece of spring steel which is bent upon itself to form a smooth rounded bottle centralizing edge 207 and the adjacent portions of which may be riveted or spot welded together as indicated at 208 to render this upper portion substantially rigid. The lower portions are left free and are shaped to form the flexible fingers 188_a which function, as in the preferred modification, to guide the bottles into their respective cells and simultaneously deflect the partitioning devices, if necessary, to place them in proper position.

The operation of these centralizing and separating devices 186_a is not very different from that of the devices 186 except that the flexible portions 203 yield or flex as shown in Fig. 27 in order to accommodate bottles of varying size, while in the devices 186 the rigid V-notched plates 187 shift bodily in their supporting notches 195. The relative positions of the separating devices 186_a for rows of average size bottles N, small size bottles S and unusually large bottles L are indicated in Figs. 22 and 24.

There is, however, one difference in operation. The separating devices 186_a are provided with only a single separating or centralizing sloping edge 107 which is somewhat longer than either 5 of the equal length legs of V-shaped notches 189 of separating plates 187. The sloping edge of the flexible portion 203 of the separating device 186_a does not under ordinary operating conditions touch the bottles as they descend through the 10 directing chutes 130_a. The long centralizing edges 107 are placed adjacent the particular rail 103_a which has supported the row of bottles previous to its descent into the bottle directing chutes. Hence as the guide plates 108 (Fig. 23) 15 of the charge-shifting frame 109 come into alignment with the rails 103_a, the bottles slide off the edges of the rails which have been supporting them, as indicated in Fig. 23, and the bottoms of those bottles which have to be shifted laterally 20 in one direction or the other immediately engage the centralizing sloping edges 207 which, because of the angle of their slope deflect the bottles as necessary to bring them into centralized position with respect to each of the directing chutes 130_a. 25 In Figs. 29 to 32, we have illustrated a modified, and, in fact, a preferred form of apparatus for causing the two lines of bottles 1_a and 2_a to converge into a single line or row 1_a for delivery to the distributing mechanism 11. This apparatus 30 does away with the pivoted switching channels 34 and the operating mechanism. In the particular embodiment of this modified apparatus which is illustrated, the row 2_a is placed in direct alignment with the row 1_a and hence the guide rails 5_a and 6_a are in line with the rails 8_a and 9_a, respectively. The row of bottles 1_a is directed 35 into the row 2_a as the two rows of bottles are carried forward by the wide belt 3_a. For this reason, guide rail 5_a is terminated short of the 40 front end of rail 8_a so as to leave a gap between the ends of these two rails through which the bottles from row 1_a may pass, and the bottles are directed through this gap by means of a deflecting guide 209 of guide rail 4_a which connects the 45 end of this rail with the front end of guide rail 8_a. It will be understood that, if desired, the lane 1_a may be alined midway between lanes 1_a and 2_a instead of being placed directly in line with lane 2_a. 50 The bottles being fed toward the machine in the two feed lines 1_a and 2_a may, in some cases, be in solid lines, that is, in contact with one another, while in other cases the bottles in one or both of these feed lines may be spaced apart to 55 a greater or a less extent. The speed of belt 3_a is adjusted with relation to the speed or rate of advancement of the bottles in the feed lines 1_a and 2_a to cause the bottles on belt 3_a in at least one of the two lanes 4_a and 6_a to be spaced apart 60 from one another by a distance not less than the diameter of the bottles in order to provide spaces into which the bottles from the other lane may be received when the two lanes are converged into one another by means of the deflecting 65 guide 209. As long as the bottles advancing in the two lanes 4_a and 6_a are staggered with respect to one another, the two lanes are converged into a single line which advances along the lane 8_a merely by 70 the deflecting action of guide 209. Occasionally, however, a pair of bottles will be advanced along the lanes 4_a and 6_a substantially abreast of one another and these would become jammed between the deflecting guide 209 and rail 9_a were 75 it not for the provision of a pair of converging

wheels 210 and 211 which are arranged, as shown in Fig. 29, opposite one another at the point where a pair of bottles advancing abreast of one another would strike the deflecting guide 209 and the opposite rail 9_a if the converging wheels 5 were not present.

Converging wheels 210 and 211 are freely rotatable discs mounted for rotation on vertical axes and preferably having ball bearings 212, as shown in Fig. 31, in order to provide great freedom of rotation. The edges of these discs project, one through a slot in guide rail 4_a and the other through a slot in guide rail 6_a a sufficient distance to engage the bottles. The converging wheels are located preferably, though not necessarily, 15 close to the bottoms of the rails and close to the surface of belt 3_a. The discs are so positioned that their axes and the points of contact between two bottles abreast of one another and between the bottles and the discs lie in a straight line 20 which is substantially perpendicular to the path of travel of the row of bottles as they approach the discs.

The edges of the discs, or converging wheels, are spaced apart slightly less than twice the 25 diameter of the average size of bottle which is to be handled by the apparatus. As a pair of bottles abreast of one another approaches the discs they make contact therewith simultaneously and the advance of both bottles is momentarily 30 stopped, or retarded. Due to variation in the friction between the belt and the bottoms of the two bottles, one bottle will be urged forward more than the other. The bottle which is urged forward the more will cause the other bottle to slide 35 backward on the belt enough to let the first bottle pass between the discs. The second bottle will immediately follow it. This places one of the bottles definitely in advance of the other and as they continue to be moved forward by the belt 40 the convergence of the diagonal extension 209 and rails 6_a will cause one of the bottles to be shifted into the space produced by the retarding action of the discs above referred to.

It is important to be able to accurately adjust 45 the positions of the two discs 210 and 211 and for this reason these discs are so mounted that they can be readily adjusted both vertically and horizontally. The arrangement of this mounting is shown in Figs. 30 and 31. The discs are each 50 provided with a hub 213 within which are the ball bearings 212 which are carried upon stud bolts 214, these being fixed at their upper ends to brackets 215. These brackets are adjustably secured to a member 216 by means of the two 55 screws 217 which pass through vertical slots in bracket 215, thus permitting the bracket to be adjusted vertically. Member 216 is secured to screws 218 to one of the guide rails 6_a or 209. These screws pass through horizontal slots in 60 member 216 for the purpose of affording horizontal adjustment.

In the modified form of apparatus shown in 65 Figs. 29 to 32, inclusive, we have provided a preferred form of guide rail which is shown in section in Fig. 32. These guide rails are provided with ribs 219 and 220 along their lower edges for engaging the bottle below the label so that the principal guiding force applied by the rail to the bottle is applied by means of these 70 ribs rather than by the flat surface of the rails. Also the principal guiding forces are applied to the bottles at a point close to the belt 3_a where the application of a lateral force has the least 75 tendency to upset the bottle, and at the same 75

time the presence of the upper portions of the rails prevents upset under even the most exceptional conditions of operation.

It is sometimes desirable to be able to pack bottles of different height on the same packing machine, or bottles packed on the same machine may be placed in cartons of different kinds. In some cartons, for example, the bottle separating strips 120-121 may extend only to about half the height of the carton, while in other cartons the separators may extend to the full height of the carton. In either case, the carton should be raised before the bottles are dropped into it by the packing mechanism, to a position such that the lower ends of the partition positioning fingers 188 extend just below the upper edges of the partitioning devices. In Fig. 33 a mechanism is illustrated by means of which the height to which the carton is elevated may be readily adjusted.

In Fig. 33 the counterweight 134a, which descends in order to elevate supporting post 131a and platform 17a is arrested in its downward motion by means of a horizontally movable wedge member 221. This member is slidably mounted upon a cross piece 222 of the frame, and may be adjusted in its horizontal position by means of a handle 223 at the end of a rod 224 which is connected to the wedge member. This rod passes through a stirrup 225 and is provided with notches 226 for engaging the stirrup and holding the wedge member 221 in any position to which it may be adjusted. Thus by adjusting the handle 23 to the left, as viewed in Fig. 33, weight 134a is permitted to descend further and therefore the position to which platform 17a and carton 15a is elevated will be raised. In this way the height to which the carton is elevated may be adjusted in proper relation to the height of the particular carton and the height of the partitioning devices within it.

In Fig. 33 it will be noted that slight changes have been made in certain other details of construction, for example, the bar 135a upon which weight 134a is mounted is connected to the supporting post 131a by a link instead of by a chain, and the latch 140a which is actuated by foot pedal 16a engages a shoulder 227 on bar 135a, instead of engaging a shoulder on the table 17a.

In Fig. 34 we have illustrated a modified form of carton supporting table 17b. The construction of this table avoids the necessity of providing the stationary roller 127 (see Fig. 9) for causing the tilting of carton 15 when it is desired to discharge the filled carton onto the roller conveyor 18. In the modified construction, the frame for table 17b is pivoted to the supporting post 131b slightly to the right of the center of the table, as indicated by numeral 228. The offsetting of the pivot means 228 causes the table 17b normally to assume a horizontal position in which it is held by means of a cross member 229 on the supporting post structure which engages the lower edge of the table frame. When the table is lowered, however, the left hand edge of the table strikes a fixed stop 230 causing the table to tilt to the position shown in dotted lines in Fig. 34 which places the slope of the table in alignment with that of the roller conveyor 18a which causes the filled carton to be discharged from the machine onto this roller table.

It will be understood that changes may be made in the particular apparatus which we have chosen for the purpose of illustrating our present invention without departing from the scope

of the invention which is defined in the appended claims. It will be understood that the specific features of the invention render it especially adapted to handle round or rounded articles, and the term "bottle" as used in this specification and in the appended claims is intended to include not only ordinary glass bottles, but also "cans," whether made of metal, paper or other material, as well as other cylindrical or rounded containers or articles. In its broader aspects, however, the invention is not limited to round or rounded containers or articles, but the broad features of the invention are capable of utilization in packing containers and articles of other shapes, such as those of square or rectangular outline.

We claim:

1. In an article packing machine means for advancing articles in upright position in one or more parallel rows, means for receiving the articles from the advancing means comprising for each row a stationary rail for engaging the bottoms of the articles and a pair of guides for the opposite sides of each row, means for supporting a case therebeneath, and means for shifting laterally the pair of guides for each row so as to bring the rail and one of said guides into substantially vertical alignment thereby causing the articles to descend between the rails into the case. 30

2. In an article packing machine means for advancing articles in upright position in one or more parallel rows, means for receiving the articles from the advancing means comprising a plurality of supporting rails and a laterally shiftable frame, the rails being arranged in alignment with the respective rows and spaced apart to permit the articles to fall between them, the laterally shiftable frame including a plurality of parallel guide plates having the same spacing as the supporting rails the said plates serving to preserve the alignment of the articles in rows, means for supporting a case, and means for shifting the laterally shiftable frame to cause the charge to descend between the supporting rails into the case. 45

3. In an article packing machine, a plurality of spaced parallel article supporting rails for supporting the articles in upright position, a shiftable frame carrying spaced parallel article guides arranged above the rails, the rails normally being disposed between respective pairs of guides so as to support a row of articles between each pair, means for feeding articles onto the rails to form a charge, article directing means below the tops of the rails, a table for supporting a case beneath the directing means in position to receive the charge of articles therefrom, and means for shifting said frame to bring the guides thereof into substantially vertical alignment with the article supporting rails thereby causing the articles thereon to drop through the directing means into the case. 55

4. In an article packing machine, means for feeding articles from a supply in a plurality of parallel rows in upright position, a plurality of spaced parallel rails of predetermined length to receive the articles from said rows to form a charge, article directing means beneath said rails, means for supporting a case below said rails, a shiftable frame above said rails having guiding devices adapted to receive articles from said supply and maintain them in upright position above said rails, and means for shifting said frame laterally to cause the guiding devices to 75

hold back the articles in the supply and permit the articles in the frame to descend between the rails into the case.

5. In an article packing machine, means for feeding articles from a supply in a plurality of parallel rows in upright position, a plurality of spaced parallel rails of predetermined length to receive the articles from said rows to form a charge, article-directing means beneath said rails, means for supporting a case below said rails, a shiftable frame above said rails having guiding devices adapted to receive articles from said supply and maintain them in upright position above said rails and, when shifted, causing the articles in the supply to be held back and the articles within the frame to descend into the case, means for periodically shifting said frame, means for preventing the actuation of said shifting means actuated by the articles in each row of said frame, and means for preventing the actuation of said shifting means actuated by said case.

6. In an article packing machine, means for feeding articles from a supply in a plurality of parallel rows in upright position, a plurality of spaced parallel rails of predetermined length to receive the articles from said rows to form a charge, article-directing means beneath said rails, means for supporting a case below said rails, a shiftable frame above said rails having guiding devices adapted to receive articles from said supply and maintain them in upright position above said rails and, when shifted, causing the articles in the supply to be held back and the articles within the frame to descend into the case, means for periodically shifting said frame, a latch for preventing the shifting thereof, means actuated by the articles in each row within the frame for tripping said latch, and a trip for said latch adapted to be released by the case when placed in receiving position below the rails.

7. In an article packing machine, means for feeding articles from a supply in a plurality of parallel rows in upright position, a plurality of spaced parallel rails of predetermined length to receive the articles from said rows to form a charge, article-directing means beneath said rails, means for supporting a case below said rails, a shiftable frame above said rails having guiding devices adapted to receive articles from said supply and maintain them in upright position above said rails and, when shifted, causing the articles in the supply to be held back and the articles within the frame to descend into the carton, means for periodically shifting the frame comprising a spring and a continuously rotating cam, a latch for preventing the shifting of the frame by the spring, means for releasing said latch actuated by the articles of the several rows within the frame and by the presence of a case in receiving position, said latch continuing to hold said frame against actuation by its spring until released by the rotation of said cam.

8. In a machine for packing articles in cell cases, a charge directing mechanism for charges containing a plurality of rows of articles and for directing the individual articles of a charge into their respective cells comprising a grill-like structure having a plurality of spaced elongated strips fixed in parallel relation to one another for separating and guiding the rows of articles as they pass through said mechanism into the case, members mounted between said strips subdividing the elongated spaces between each pair of adjacent strips to form article directing

chutes, each of said members having shifting means at its upper edge by means of which the individual articles of each row are separated from one another as the articles descend into the case, and said members being yieldable to permit them to adjust themselves in a direction lengthwise of said elongated spaces to compensate for variation in bottle diameter.

9. In a machine for packing bottles in cell cases, a charge directing mechanism for charges containing a plurality of rows of bottles and for directing the individual bottles of a charge into their respective cells comprising a grill-like structure having a plurality of elongated strips spaced apart the diameter of the bottles to be packed and fixed in parallel relation to one another for separating and guiding the rows of bottles as they pass through said mechanism into the case, rigid plate members mounted between said strips subdividing the elongated spaces between each pair of adjacent strips to form bottle directing chutes, each of said members having a bottle shifting notch in its upper edge by means of which the individual bottles of each row are separated from one another as the bottles descend into the case, and said members being yieldably mounted between the strips to permit them to adjust themselves in a direction lengthwise of said elongated spaces to compensate for variation in bottle diameter.

10. In a machine for packing articles in cell cases, a charge directing mechanism for charges containing a plurality of rows of articles and for directing the individual articles of a charge into their respective cells comprising a grill-like structure having a plurality of spaced elongated strips fixed in parallel relation to one another for separating and guiding the rows of articles as they pass through said mechanism into the case, members mounted between said strips subdividing the elongated spaces between each pair of adjacent strips to form article directing chutes, each of said members having article shifting means at its upper edge by means of which the individual articles of each row are separated from one another as the articles descend into the case, said members being yieldable to permit them to adjust themselves in a direction lengthwise of said elongated spaces to compensate for variation in size of the articles, and downwardly directed yieldable blade-like fingers projecting from said directing chutes to engage the cell forming structure within the case and simultaneously guide the articles into their respective cells and position the cell forming structure to prevent the articles from jamming against the edges thereof.

11. In a machine for packing articles in cell cases, a charge directing mechanism for charges containing a plurality of rows of articles and for directing the individual articles of a charge into their respective cells comprising a grill-like structure having a plurality of spaced elongated strips fixed in parallel relation to one another for separating and guiding the rows of articles as they pass through said mechanism into the case, members mounted between said strips subdividing the elongated spaces between each pair of adjacent strips to form article directing chutes, each of said members having article shifting means at its upper edge by means of which the individual articles of each row are separated from one another as the articles descend into the case, said members being yieldable to permit them to adjust themselves in a direction length-

- wise of said elongated spaces to compensate for variation in article diameter, and yieldable blade-like fingers mounted on the lower edges of said members and in spaced relation along the lower edges of said strips for engaging the upper edges of the cell forming structure within the case and simultaneously guide the articles into their respective cells and shift the various portions of said structure to their proper positions.
- 10 12. In a machine for packing bottles in cell cases, a charge directing mechanism for charges containing a plurality of rows of bottles and for directing the individual bottles of a charge into their respective cells comprising a grill-like structure having a plurality of elongated strips spaced apart the diameter of the bottles to be packed and fixed in parallel relation to one another for separating and guiding the rows of bottles as they pass through said mechanism into the case, 15 rigid plate members mounted between said strips subdividing the elongated spaces between each pair of adjacent strips to form bottle directing chutes, said members having V-shaped notches in their upper edges for shifting the individual 20 bottles of each row sufficiently to separate them from one another as the bottles descend into the case, socket means on said strips for supporting said rigid plate members to provide freedom of movement in a direction parallel to said elongated strips thereby permitting said rigid plate members to position themselves to accommodate bottles of varying diameter.
13. In a machine for packing articles in cell cases, a charge directing mechanism for charges containing a plurality of rows of articles and for directing the individual articles of a charge into their respective cells comprising a grill-like structure having a plurality of elongated strips spaced apart the diameter of the articles to be packed and fixed in parallel relation to one another for separating and guiding the rows of articles as they pass through said mechanism into the case, members mounted between said strips subdividing the elongated spaces between each 25 pair of adjacent strips to form article directing chutes, each of said members having article shifting means at its upper edge by means of which the individual articles of each row are separated from one another as the articles descend into the case, and each of said members having a flexible portion so as to permit them to shift slightly in a direction parallel to the elongated strips so as to accommodate articles of varying diameter.
14. In a machine for packing bottles in cell cases, a pair of spaced parallel strips for guiding the opposite sides of a row of bottles as they descend into the case, one of said strips serving to support the row of bottles previous to its descent, means for moving said row of bottles and said strips laterally with respect to one another to cause it to drop between the same, and means for separating said bottles as they descend and directing them into their respective cells comprising a plurality of bottle shifting members arranged transversely between said strips, each of said members having a bottle centralizing edge sloping downwardly from the top of the strip over which the bottles move in approaching the dropping position, said centralizing edges engaging the respective bottles as they descend between said strips and shifting them longitudinally of said strips so as to space the bottles apart and centralize them with respect to their respective cells.

15. In an article packing machine, the combination of a charge assembling mechanism for assembling a charge of articles to be packed, charge-directing mechanism for directing the charge downwardly from the assembling mechanism into a case, a vertically shiftable platform for holding the case arranged beneath the charge-directing mechanism, means for elevating the platform to raise the mouth of the case into engagement with the bottle directing mechanism 10 to receive a charge and for lowering the filled case, a carton conveyor arranged alongside of said platform, and means for engaging the filled carton at one side of its center as the platform descends to tilt the carton and to cause it to slide 15 onto the carton conveyor.

16. In an article packing machine, the combination of a charge-assembling mechanism for assembling a charge of articles to be packed, charge-directing mechanism for directing the charge downwardly from the assembling mechanism into a case, a vertically shiftable supporting means having a platform pivoted thereto for holding the case arranged beneath the charge-directing mechanism, means for elevating the platform to raise the mouth of the case into engagement with the article-directing mechanism to receive a charge and for lowering the filled case, a carton conveyor arranged alongside of said platform in its lowered position, means for 30 maintaining said platform horizontal during the raising and lowering of the carton thereon, and a stop fixed adjacent the lower end of the path of movement of the platform for tilt-35 ing the same and causing the carton to slide onto the carton conveyor.

17. In a bottle packing machine, a single continuously moving belt having a width sufficient to support thereon the desired number of rows of bottles to form a charge for the case, guiding devices over said belt for causing the bottles to advance in a plurality of rows, a plurality of bottle supporting rails arranged in alinement with said rows to receive bottles therefrom to form a charge, said rails being spaced from one another 40 by the diameter of the bottles and forming vertical guides for directing said rows of bottles downwardly into a case, a shiftable frame having guide plates arranged in alinement with said guiding devices over the belt to support the rows 45 of bottles forming the charge, and means for shifting said frame to bring said plates into alinement with said rails to cause the bottles to drop 50 between the rails into the case.

18. In an article packing machine, a conveyor, 55 guiding devices associated therewith for guiding articles thereon in a plurality of rows, a plurality of article supporting rails arranged in alinement with said rows to receive the articles therefrom to form a charge, said rails being spaced 60 from one another by the thickness of the articles and forming vertical guides for directing said rows of articles downwardly into a case, guide plates arranged in alinement with said guiding devices to support the rows of articles forming 65 the charge, and means for shifting said plates into alinement with said rails to cause the articles to drop between the rails into the case.

19. In an article handling machine, a conveyor, 70 guiding devices associated therewith for guiding articles thereon in a plurality of rows, a plurality of article supporting rails arranged in alinement with said rows to receive articles therefrom, said rails being spaced from one another by the thickness of the articles and forming vertical guides 75

for directing said rows of articles downwardly onto a support, guide plates arranged in alinement with said guiding devices to support the rows of articles on said rails, and means for shifting said plates into alinement with said rails to cause the articles to drop between the rails onto the support.

20. In a machine for packing bottles in cell cases, a pair of spaced parallel strips for guiding the opposite sides of a row of bottles as they descend into the case, one of said strips serving to support the row of bottles previous to its descent, means for moving said row of bottles and said pair of strips laterally with respect to one another to cause said row to drop between the same, means for separating said bottles as they descend and directing them into their respective cells comprising a plurality of bottle-shifting members arranged transversely between said strips, each of said members having a V-shaped notch in its upper edge, adapted to be engaged by the respective bottles as they descend between said strips and shift them longitudinally of said strips so as to space the bottles apart and centralize them with respect to their respective cells.

21. In a machine for packing bottles in cell cases, a pair of spaced parallel strips for guiding the opposite sides of a row of bottles as they descend into the case, one of said strips serving to support the row of bottles previous to its descent means for moving said row of bottles and said pair of strips laterally with respect to one another to release said row and cause it to drop between the same, and means for separating said bottles after they are released and directing them into their respective cells comprising a plurality of bottle-shifting members arranged transversely between said strips, each of said members having a bottle-centralizing edge sloping downwardly from the top of the strip which supports the bottles, said centralizing edges engaging the respective bottles after their release and shifting them longitudinally of said strips so as to space the bottles apart and centralize them with respect to their respective cells.

22. In a machine for packing bottles in cell cases comprising an elongated chute having substantially vertical walls appropriately spaced to accommodate a row of articles and guide it downwardly, means for delivering a row of articles into said chute, and cross members arranged between the walls of said chute to subdivide it into a plurality of chutes for directing individual articles into their respective cells, each of said members having article shifting means at its upper edge by means of which the individual articles are separated from one another as the articles descend into the case, said members being yieldably arranged so as to permit them to adjust themselves in a direction lengthwise of the elongated chute to accommodate articles of varying thickness.

23. In a machine for packing articles in cell cases, an elongated chute having parallel side walls adapted to receive articles one row at a time and direct them downwardly into a case, means for delivering articles into said chute, cross members subdividing the elongated chute into a plurality of chutes for directing individual articles into their respective cells, each of said cross members having article-shifting means at its upper edge by which the individual articles are separated from one another as they descend into the case, said cross members comprising rigid plates yieldably mounted to permit them to adjust

themselves in a direction lengthwise of said elongated chute to compensate for variation in article thickness.

24. In a machine for packing articles in cell cases, an elongated chute having parallel side walls adapted to receive articles one row at a time and direct them downwardly into a case, means for delivering articles into said chute, cross members subdividing the elongated chute into a plurality of chutes for directing individual articles into their respective cells, each of said cross members having article-shifting means at its upper edge by which the individual articles are separated from one another as they descend into the case, each of said cross members having a flexible portion so as to permit them to yield to adjust themselves in a direction lengthwise of said elongated chute to compensate for variation in article diameter.

25. In a machine for packing articles in cell cases, an elongated chute having parallel side walls adapted to receive articles one row at a time and direct them downwardly into a case, means for delivering articles into said chute, cross members subdividing the elongated chute into a plurality of chutes for directing individual articles into their respective cells, each of said cross members having article-shifting means at its upper edge by which the individual articles are separated from one another as they descend into the case, said cross members being yieldable lengthwise of said elongated chute to permit them to adjust themselves to compensate for variation in article thickness, and yieldable blade-like fingers at the lower edges of said cross members and on the walls of said chute intermediate the cross members for engaging the upper edges of the cell-forming structure within the case to guide the articles into their respective cells simultaneously and shift various portions of said structure to their proper positions to receive the articles.

26. In a machine for packing bottles in cell cases, an elongated chute having parallel side walls adapted to receive bottles one row at a time and direct them downwardly into a case, means for delivering bottles into said chute, cross members subdividing the elongated chute into a plurality of chutes for directing individual bottles into their respective cells, each of said cross members having a V-shaped notch in its upper edge by which the individual bottles are separated from one another as they descend into the case, said cross members being yieldable lengthwise of said elongated chute to permit the members to adjust themselves to compensate for variation in bottle diameter.

27. In a machine for packing bottles in cell cases, an elongated chute having parallel side walls adapted to receive bottles one row at a time and direct them downwardly into a case, means for delivering bottles into said chute, rigid plate cross members subdividing the elongated chute into a plurality of chutes for directing individual bottles into their respective cells, each of said rigid plates having a V-shaped notch in its upper edge by which the bottles are separated from one another as they descend into the case, said plates being yieldably mounted to permit them to adjust themselves in a direction lengthwise of said elongated chute to compensate for variation in bottle diameter.

28. In a machine for packing bottles in cell cases, an elongated chute having parallel side walls adapted to receive bottles one row at a time and direct them downwardly into a case, means

for delivering bottles into said chute, cross members subdividing the elongated chute into a plurality of chutes for directing individual bottles into their respective cells, each of said cross members having a V-shaped notch in its upper edge by which the individual bottles are separated from one another as they descend into the case, said cross members being yieldable lengthwise of said elongated chute to permit the members to adjust themselves to compensate for variation in bottle diameter, yieldable blade-like fingers at the lower edges of said cross members and on the walls of said chute intermediate the cross members for engaging the upper edges of the cell-forming structure within the case to guide the bottles into their respective cells simultaneously and shift various portions of said structure to their proper positions to receive the bottles.

29. In a machine for packing articles in cases, a conveyor, guides associated therewith for guiding a row of articles thereon, a rail arranged in alignment with said row to receive therefrom and support articles to form a charge, a member parallel to and spaced from the rail by the thickness of the articles, said member and rail forming vertical guides for directing the articles downwardly into a case, guide plates arranged in alignment with said guides to engage the sides of the row of articles forming the charge, and means for shifting said plates to bring them into vertical alignment with said rail and member respectively to cause the articles to drop between the rail and said member into the case.

30. In a machine for packing articles in cell cases, a conveyor, guides associated therewith for guiding a row of articles thereon, a rail arranged in alignment with said row to receive therefrom and support articles to form a charge, a member parallel to and spaced from the rail by the thickness of the articles, an elongated chute including said rail and member as its side walls for directing the articles downwardly into a case, guide plates arranged in alignment with said guides to engage the sides of the row of articles forming the charge, means for shifting said plates to bring them into vertical alignment with said rail and member respectively to cause the articles to drop through the chute into the case, and cross members subdividing the elongated chute to form directing chutes for the individual articles, each of said cross members having article-shifting means at its upper edge by which the articles are separated from one another as they descend into the case.

31. In a machine for packing articles in cell cases, a conveyor, guides associated therewith for guiding a row of articles thereon, a rail arranged in alignment with said row to receive therefrom and support articles to form a charge, a member parallel to and spaced from the rail by the thickness of the articles, an elongated chute including said rail and member as its side walls for directing the articles downwardly into a case, guide plates arranged in alignment with said guides to engage the sides of the row of articles forming the charge, means for shifting said plates to bring them into vertical alignment with said rail and member respectively to cause the articles to drop through the chute into the case, and cross members subdividing the elongated chute to form directing chutes for the individual articles, each of said cross members having article-shifting means at its upper edge by which the articles are separated from one another as they descend into the case, said cross members being yieldable lengthwise of said elongated chute to permit the mem-

bers to adjust themselves to compensate for variation in article size.

32. In a machine for packing articles in cell cases, a conveyor, guides associated therewith for guiding a row of articles thereon, a rail arranged in alignment with said row to receive therefrom and support articles to form a charge, a member parallel to and spaced from the rail by the thickness of the articles, an elongated chute including said rail and member as its side walls for directing the articles downwardly into a case, guide plates arranged in alignment with said guides to engage the sides of the row of articles forming the charge, means for shifting said plates to bring them into vertical alignment with said rail and member respectively to cause the articles to drop through the chute into the case, and cross members subdividing the elongated chute to form directing chutes for the individual articles, each of said cross members having article-shifting means at its upper edge by which the articles are separated from one another as they descend into the case, said cross members comprising rigid plates yieldably mounted to permit them to adjust themselves in a direction lengthwise of said elongated chute to compensate for variation in article size.

33. In a machine for packing articles in cell cases, a conveyor, guides associated therewith for guiding a row of articles thereon, a rail arranged in alignment with said row to receive therefrom and support articles to form a charge, a member parallel to and spaced from the rail by the thickness of the articles, an elongated chute including said rail and member as its side walls for directing the articles downwardly into a case, guide plates arranged in alignment with said guides to engage the sides of the row of articles forming the charge, means for shifting said plates to bring them into vertical alignment with said rail and member respectively to cause the articles to drop through the chute into the case, and cross members subdividing the elongated chute to form directing chutes for the individual articles, each of said cross members having article-shifting means at its upper edge by which the articles are separated from one another as they descend into the case, each of said cross members having a flexible portion so as to permit them to yield to adjust themselves in a direction lengthwise of said elongated chute to compensate for variation in article size.

34. In a machine for packing articles in cell cases, a conveyor, guides associated therewith for guiding a row of articles thereon, a rail arranged in alignment with said row to receive therefrom and support articles to form a charge, a member parallel to and spaced from the rail by the thickness of the articles, an elongated chute including said rail and member as its side walls for directing the articles downwardly into a case, guide plates arranged in alignment with said guides to engage the sides of the row of articles forming the charge, means for shifting said plates to bring them into vertical alignment with said rail and member respectively to cause the articles to drop through the chute into the case, and cross members subdividing the elongated chute to form directing chutes for the individual articles, each of said cross members having article-shifting means at its upper edge by which the articles are separated from one another as they descend into the case, and yieldable blade-like fingers at the lower edges of said cross members and on the walls of said chute intermediate the cross members for engaging the

upper edges of the cell-forming structure within the case to guide the articles into their respective cells simultaneously and shift various portions of said structure to their proper positions 5 to receive the articles.

35. In a machine for packing articles in cell cases, a conveyor, guides associated therewith for guiding a row of articles thereon, a rail arranged in alinement with said row to receive therefrom 10 and support articles to form a charge, a member parallel to and spaced from the rail by the thickness of the articles, an elongated chute including said rail and member as its side walls for directing the articles downwardly into a case, 15 guide plates arranged in alinement with said guides to engage the sides of the row of articles forming the charge, means for shifting said plates to bring them into vertical alinement with said rail and member respectively to cause the 20 articles to drop through the chute into the case, and cross members subdividing the elongated chute to form directing chutes for the individual articles, each of said cross members having article-shifting means at its upper edge by which 25 the articles are separated from one another as they descend into the case, said cross members being yieldable lengthwise of said elongated chute to permit the members to adjust themselves to compensate for variation in article size, 30 and yieldable blade-like fingers at the lower edges of said cross members and on the walls of said chute intermediate the cross members for engaging the upper edges of the cell-forming structure within the case to guide the articles 35 into their respective cells simultaneously and shift various portions of said structure to their proper positions to receive the articles.

36. In a machine for packing bottles in cell cases, charge-forming mechanism for assembling 40 a charge of bottles in one or more rows, a chute for directing the charge into a case, means for releasing the charge from the charge-forming mechanism into the chute, said chute having bottle-separating members arranged to engage 45 the lower ends of the bottles after their release from the charge-forming mechanism to space

the bottles apart for entry into their respective cells, said members having bottle-shifting means at their upper edges, and being yieldable lengthwise of a row to permit the members to adjust themselves in a direction lengthwise of the row 5 to compensate for variation in bottle diameter.

37. In an article packing machine a conveyor for advancing a supply of articles to be packed, guiding members associated with the conveyor for causing the articles to advance along the conveyor 10 in a plurality of rows, a frame carrying guide plates arranged in alinement with said guiding members adapted to receive therebetween from said conveyor articles to form a charge to be packed, a grill-like structure arranged beneath 15 said plates having downwardly directed chutes for delivering the individual articles into a case and including parallel strips spaced horizontally with respect to said plates so as to support the rows of bottles therebetween, and means for horizontally shifting said grill-like structure and said plate-supporting frame with respect to one another so as to cause the charge of articles therein to be discharged through the grill-like structure 20 into the case. 25

38. In an article packing machine a conveyor for advancing a row of articles, guide members associated with the conveyor, a frame carrying a pair of guide plates in alinement with said guiding members said plates being adapted to 30 receive therebetween from said conveyor a plurality of articles to form a row of the charge to be packed, a grill-like structure arranged beneath said plates having downwardly directed chutes for delivering the individual articles into 35 a case and including a pair of parallel strips spaced horizontally with respect to said plates so as to cause one of said strips to support the row of articles which is between these plates, and means for horizontally shifting said grill-like 40 structure and said plates with respect to one another so as to cause the articles therein to be discharged through the grill-like structure into the case. 45

CERTIFICATE OF CORRECTION.

Patent No. 2,219,827.

October 29, 1940.

WALLACE D. KIMBALL, ET AL.

It is hereby certified that error appears in the printed specification of the above numbered patent requiring correction as follows: Page 6, first column, line 65, for the word "suitable" read --shiftable--; page 14, first column, line 46, claim 22, for "bottles" read --articles--; and that the said Letters Patent should be read with this correction therein that the same may conform to the record of the case in the Patent Office.

Signed and sealed this 10th day of December, A. D. 1940.

(Seal)

Henry Van Arsdale,
Acting Commissioner of Patents.
